DESIGN FOR A CHILD'S FEEDING AND PLAY TABLE

Alfred E. Puls, Cleveland, Ohio, and Edward R. Swenson, Metropolis, Ill., assignors to Metropolis Bending Company, Metropolis, Ill., a corporation of Illinois

Application March 20, 1944, Serial No. 112,972

Term of patent 14 years

(Cl. D33—14)

To all whom it may concern:

Be it known that we, Alfred E. Puls and Edward R. Swenson, citizens of the United States, residing, respectively, at Cleveland, in the county of Cuyahoga and State of Ohio, and Metropolis, in the county of Massac and State of Illinois, have invented a new, original, and ornamental Design for a Child's Feeding and Play Table, of which the following is a specification, reference being had to the accompanying drawing, forming

part thereof, wherein the figure is a perspective view of a child's feeding and play table, showing our new design. The dominant features of the design reside in the portions illustrated in full lines.

We claim:

The ornamental design for a child's feeding and play table, as shown and described.

ALFRED E. PULS.
EDWARD R. SWENSON.
